UNITED STATES PATENT OFFICE.

FRANK M. LUCORE, OF LINCOLN, NEBRASKA.

CAR-REPORT BOOK.

SPECIFICATION forming part of Letters Patent No. 727,164, dated May 5, 1903.

Application filed April 14, 1902. Serial No. 102,771. (No model.)

To all whom it may concern:

Be it known that I, FRANK M. LUCORE, a citizen of the United States, residing at Lincoln, county of Lancaster, and State of Nebraska, have invented certain new and useful Improvements in Car-Report Books, of which the following is a specification.

This invention relates particularly to an improvement in books for keeping car-reports and to the special construction and arrangement thereof and of the form sheet or sheets upon which such reports are transcribed; all of which will more fully herein-after appear.

15 The principal object of this invention is to provide a simple, economical, and efficient book for car-reports.

A further object of the invention is to provide a simple, economical, and efficient book 20 with a cover and form-sheets removably and flexibly secured together.

Further objects of the invention will appear from an examination of the drawings and the following description and claims.

25 The invention relates to a car-report book provided with a cover formed of a front portion, a back portion, and an intermediate portion flexibly secured together.

The invention relates, further, to a car-report book provided with a cover formed of a back portion, a front portion, and an intermediate portion flexibly secured together and form-sheets detachably secured thereto between the intermediate cover and the front 35 and back covers.

The invention relates, further, to a car-report book provided with a removable form-sheet having two sets of forms printed on each side of the blank in reverse relation to 40 each other, the blanks on each side of the sheet forming a continuation one of the other and in reverse relation.

The invention consists in the features, details, and combinations hereinafter described 45 and claimed.

In the accompanying drawings, Figure 1 is a blank sheet showing one side of a removable form-sheet for a car-report book constructed in accordance with my improvements; Fig. 2, a perspective view of the book with the form-sheets in removable position and constructed in accordance with these im-

provements; and Fig. 3, a cross-sectional view of the same, taken on line 3 of Fig. 2 looking in the direction of the arrow. 55

In the art to which this invention relates it is well known that there is a great deal of trouble and expense involved in the keeping of reports of the number and kinds of freight-cars handled by the various freight-conductors of the different railroads. At present it is customary for freight-conductors to have a book in which to keep a record of the cars handled, &c., and then at the end of each run to transfer from said book to a report-sheet the necessary information to make their report to the car-accountant of the railroad, the book being retained by the conductor until full, when it is turned over to the train-master and a new book issued. It 70 will be seen, therefore, that this entails a tremendous amount of labor and expense. Take, for instance, on a single run of one of the large roads of the railroads of the country where two hundred freight-trains are 75 handled each day on one division thereof with twenty-five cars to the train, it means that five thousand cars are handled each day, or one hundred and fifty thousand each thirty-day month. Figuring car-initials as averaging four letters and car-numbers as averaging four figures, the movement of each car on one division of the road would therefore require something like twenty characters in making out their reports to the car-accountant, or a total of three million characters a 80 month on such division alone. The principal object of this invention, therefore, is to provide means by which a large saving of this initial and number writing can be obtained 85 by providing a book and blank of such construction and arrangement that the book record and report for the car-accountant are written simultaneously in duplicate and in proper shape for the car-accountant and 90 train-master, one copy of which may be forwarded to the car-accountant and the other turned over to the train-master or retained by the conductor. It will therefore be seen that at least one-half of the labor and expense 95 will be saved by such improvement, and also that the danger of errors liable to result from transcribing from the memorandum-book to the report-sheet for the car-accountant is en-

tirely obviated, all of which will be appreciated by those skilled in the art.

In constructing a book in accordance with these improvements and describing particularly the form-sheet to be used therein I make a sheet having form portions *a* and *b* on each side and perforated at *c* to permit the folding thereof. The side of the sheet, as shown in the figure, contains the proper heading, with 10 columns arranged underneath to receive the report of the freight-conductor or trainman, and is printed with the main heading on the form portion *a* and the continuation thereof on the form portion *b* in reverse relation to 15 that shown on the form portion *a*—that is, the heading of the form portion *a* begins at the top, while that of the form portion *b*, begins at the bottom. The other side of the sheet is likewise printed; but the form portion 20 *a* is on the opposite side of the portion *b*, with its heading at the top, the reason being that when the form portion *a* is being used the sheet is folded along the perforated line and a sheet of interleaving carbon placed between 25 the two sheets, so that the writing on the form portion *a* will be transferred to the form portion on the sheet, thus making two records thereof. In using these sheets I make a cover portion for the book of peculiar formation and 30 which is applicable to these kinds of sheets only. This cover has a front portion *d*, a back portion *e*, and an intermediate portion *f*, practically making two books, all flexibly secured or hinged together at *g*, so that they may be 35 closed or moved in the direction indicated by the dotted arrows in Fig. 3. In using this cover portion with the form-sheets, as above described, one form-sheet is folded with a sheet of carbon-paper and placed, as shown 40 in Fig. 2, with the main heading *a* of the same between the front cover and the intermediate cover. A second sheet is folded with a sheet of interleaving carbon-paper and with the heading on the form portion *b* at the top and 45 inserted between the intermediate and back covers. This arrangement is necessary and desirable in that it will be seen from an inspection of Fig. 1 that a record of ninety cars 50 may be kept—forty on the main form portion of the sheet and fifty on the supplementary form portion *b*. In making the first forty entries they are made on the main form portion of the sheet, arranged between the front and intermediate covers, and instead of it being necessary for the conductor to take out 55 the sheet and place a new one to make reports for additional cars or to reverse carbon-sheet *en route* all he has to do is to make such additional report of cars on the sheet 60 interposed between the intermediate and back covers. These form-sheets are loosely held in position, preferably by means of a rubber band *h*, passed around the sheets where they are adjacent to the interleaving cover.

65 The principal advantages incident to the use of a car-report book constructed in accordance with these improvements are, first,

the enormous saving of labor and expense by conductors and trainmen; second, the obviating of errors arising from the old methods; 70 third, the saving of expense in the car-accountant's office in that the conductor's sheets can be filed therein, thus obviating the necessity for the usual retranscribing of the same, and, fourth, the facility with which 75 records may be kept and inspected, all of which will be understood and appreciated by those skilled in the art.

I claim—

1. A car-report book of the class described 80 provided with a removable form-sheet having two blanks printed on each side of the sheet in inverted relation to each other so that one of the blanks in order to be read must be held in inverted position with reference to the 85 other, the blanks on each side of the sheet arranged so that one forms a continuation of the other or main form, substantially as described.

2. In a car-report book of the class de- 90 scribed, a duplicate form-sheet having two blank forms on one side—a main and a supplementary—arranged in inverted relation to each other so that one of the blanks in order to be read must be held in inverted position with reference to the other, and two similar blank forms on the opposite side of the same sheet—main and supplementary—so arranged that when the sheet is folded the blank form on one side corresponds or registers with its duplicate form on the opposite side, substantially as described.

3. In a car-report book of the class de- 95 scribed, a duplicate form-sheet having a main form with its heading at the top and a 105 supplementary continuation thereof with its heading at the bottom on one side of the sheet and inverted, and similar forms on the opposite side of the same sheet so arranged that when the sheet is folded the blank form 110 on one side corresponds or registers with its duplicate form on the opposite side, substantially as described.

4. In a car-report book of the class de- 115 scribed, the combination of two flexibly-connected outer-cover leaves, an intermediate inner-cover leaf flexibly connected therewith, a blank form-sheet removably arranged on one side of the intermediate cover-leaf and provided with duplicate forms thereon, each of a width exceeding that of either cover-leaf and having carbon-paper arranged 120 between such blank forms, such forms consisting of a main form with its heading at the top and a supplementary continuation 125 thereof with its heading at the bottom on one side of the sheet in inverted relation to each other, and similar forms arranged in the same relation to each other on the opposite side of the sheet so that when the sheet is folded the forms on one side thereof register with the duplicate forms on the opposite side and a similar separable and independently-removable blank form-sheet removably 130

arranged on the opposite side of the intermediate cover-leaf provided with duplicate blank forms arranged in the same manner as those on the blank form-sheet at the opposite side of the inner-cover leaf, each of a width exceeding that of either cover-leaf and having carbon-paper arranged between such blank forms, and means for removably se-

curing such blank form-sheets in position on opposite sides of the inner-cover leaf, substantially as described.

FRANK M. LUCORE.
